UNITED STATES PATENT OFFICE.

HEINRICH TOUSSAINT, OF CASSEL-WILHELMSHÖHE, GERMANY, ASSIGNOR TO SCHMIDT'SCHE HEISSDAMPF-GESELLSCHAFT M. B. H., OF CASSEL-WILHELMSHÖHE, GERMANY.

FAN FOR INDUCED DRAFT.

1,182,863.

Specification of Letters Patent.

Patented May 9, 1916.

Application filed January 25, 1916. Serial No. 74,097.

To all whom it may concern:

Be it known that I, HEINRICH TOUSSAINT, a subject of the German Emperor, King of Prussia, residing at Cassel-Wilhelmshöhe, 5 Germany, have invented certain new and useful Improvements in Fans for Induced Draft, of which the following is a specification.

My invention relates to rotatable fans, for 10 induced draft, when placed in the lower part of a chimney or stack and operated so as to force the fire gases upwardly therein.

Fans placed in the lower part of a chimney or stack, as above mentioned, are not 15 new. Such arrangements, however, have not been entirely satisfactory, owing to the fact that the fan bearings have been exposed, to a greater or less extent, to the intensely hot flue gases; and it has long been 20 recognized that, to avoid the intense heat thereby produced, said bearings should be removed as far as possible from the influence of such gases. In prior arrangements, 25 of which I have knowledge, this object has only been partially attained, inasmuch as it has only been possible to locate the lower or thrust bearing out of the stream of hot gases while leaving the upper or neck bearing exposed thereto.

30 It is the object of the present invention to improve the just described and hitherto used arrangement by not only removing both bearings from the stream of hot flue gases, but by, furthermore, providing means to 35 actually cool the neck bearing by flowing thereover a stream of cold air. This requirement of a stream of cold air flowing over the neck bearing is almost as essential as that the neck bearing be removed from 40 the stream of flue gases, inasmuch as the neck bearing is, in any case, substantially nearer the fan than the thrust bearing and is consequently affected by the heat of the 45 said gases in much greater degree. Over and beyond this, a great deal of heat, from the region of the fan, reaches the neck bearing by conduction through the fan shaft.

50 My invention will be better understood by referring to the accompanying drawings, in which—

Figure 1 represents one form of my invention as applied to the chimney of a stationary steam plant, the chimney being shown in section; Figs. 2 and 3 represent, 55 respectively, front and side elevations of a

modified form of my invention as applied to a marine boiler plant; and Figs. 1^a and 1^b show, respectively and on an enlarged scale, axial sections through the neck bearing and the thrust bearing.

60

Referring to Fig. 1, a fan *b* is located near the bottom of a chimney *b'*, and fixed to a shaft *c* which is mounted to rotate in a frame *d*, having a neck bearing *d'* and a thrust bearing *d''*. The frame *d* is supported by brackets *g*, *g* and provided with a downwardly extended portion *f* carrying a motor *e*, (electric or other preferred suitable type) the shaft of which is directly connected at *n* to the shaft *c*. The frame 70 with its bearings is situated, as may be seen by the drawing, in a chamber *b*² opening from, or recessed into, the bottom of the chimney. This chamber is covered by a plate *i* and is also provided with a lateral 75 opening having a door *h*. The plate *i* has a central opening *k* through which projects the upper part of the frame *d*, with the neck bearing *d'*, and from this opening is extended a tapered air conduit sleeve *l* which 80 is spaced from but surrounds the projecting portion of the frame and that portion of shaft *c* above the frame and reaches substantially to the fan *b*. The door *h*, when opened, gives access to the fan, its mounting 85 and motor, as a whole for purposes of cleaning, lubrication, repair and the like; and the door is so arranged that, even when closed, a certain amount of cold air, from outside 90 the chimney, may pass therethrough.

In operation, the rotation of the fan forces the hot flue gases upwardly, thereby establishing the desired induced draft and preventing said gases, and any ashes which they may have carried from the fire box, 95 from entering the top of the air conduit *l* so as to heat shaft *c* and neck bearing *d'*. Furthermore, the cold air which enters chamber *b*², through door *h*, will be sucked upwardly by the fan so as to establish a 100 continuously flowing stream through air conduit *l*, which stream will tend to cool the neck bearing *d'* and the shaft *c* and, hence, to lessen the amount of heat which can be carried from the fan to the neck bearing by 105 conduction through the shaft *c*.

In the modified form of my invention intended for marine boilers, as shown in Figs. 2 and 3, the stack in which the fan is placed is formed by the junction of the individual 110

exit flues, *q* and *r*, of a pair of similar boilers *o* and *p* arranged side by side in the usual way. The frame *d*, carrying the neck and thrust bearings *d'* and *d''*, and the driving motor *e'* (shown as a steam turbine in this case), is supported in the chamber or space *t*, formed and laterally bounded by the flues *q* and *r*, as they unite to form the main stack. The air conduit or sleeve *l* extends upwardly from an opening made in the upper central part of this chamber.

10 The fan proper may be cleaned through an opening *v*, made in the wall of the stack at the level of the fan and ordinarily covered by a suitable door.

15 Having described my invention I claim:

1. In combination with a vertical stack, a bottom for said stack provided with an opening which connects with an air supply 20 and from which extends an upwardly di-

rected air conduit, a rotatable fan in said stack just above the top of said air conduit, a shaft for said fan within and spaced from said air conduit, a mounting for said shaft provided with a neck and thrust bearing below the top of said conduit.

2. In combination, a pair of laterally disposed exit flues which unite so as to form a stack, a rotatable fan in the lower part of said stack, a shaft for said fan, and a mounting 30 for said shaft provided with a neck and thrust bearing and located in the space below the stack which is bounded by the inner walls of the exit flues, there being an opening connecting said stack and said space 35 through which said shaft passes and through which air may flow upwardly over the shaft.

In testimony whereof I have hereunto set my hand.

HEINRICH TOUSSAINT.
